Application June 2, 1947, Serial No. 751,926

18 Claims. (CL 171—252)

1

Our invention relates to improvements in a semi-automatic lifting, braking and jacking system for vertical water-wheel generators, or other vertical-shaft rotating machines. Vertical water-wheel generators are large machines in which the rotor-member is positioned by suitable guide-bearing-means, and in which the weight of the rotor-member is supported by a thrust-bearing, comprising a runner carried by the rotor-member, a plurality of thrust-bearing shoes carried by the stator-member and engaging the runner, and an oil-chamber for oil in which said thrust-bearing shoes and at least the lower surface of said runner are immersed. These machines have heretofore been provided with braking and jacking means, comprising a brake-ring carried by the rotor-member, and a plurality of hydraulic jacks carried by the stator-member and having brake-shoes, on their tops, in a position to engage the brake-ring in an elevated position of the jacks. Heretofore, the hydraulic jacks have been provided with two different operating-means, one for braking, and the other for jacking.

For braking purposes, air was fed into the jacks, at a moderate pressure of the order of 100 p. s. i. (pounds per square inch), so as to press the brake-shoes up against the brake-ring with a pressure which is much too small to support the weight of the rotor-member, but which suffices to bring the rotor-member to standstill and to hold it at standstill against any leakage-drag of the turbine to which it is connected. This braking-operation has heretofore been inaugurated after first letting the machine decelerate, of its own accord, down to half-speed, or some other predetermined speed intermediate between full-speed and standstill, thus minimizing the braking-burden.

For jacking purposes, oil has heretofore been fed into the jacks, by means of a high-pressure oil-pump, which is capable of delivering oil slowly, but at a very great pressure, such as 2000 p. s. i., which produces enough lifting-force to support the weight of the rotor-member and lift it so that the runner no longer rests on the thrust-bearing shoes. Jacking operations have been necessary, at more or less rare intervals, for the purpose of enabling workmen to service and inspect the thrust-bearings, and for other purposes.

Heretofore, a jacking operation, even though no time was consumed in inspection and servicing, has been a rather slow operation, requiring some half-hour or three-quarters of an hour. First, the air-pressure had to be shut off from the hy-

2

draulic jacks, which had been in use as brakes. Then the air in the system had to be flushed out with oil, after which the jacks were lifted by using the oil-pump to pump oil into their cylinders. As the brake-shoes were some half-inch below the brake-runner, in the down-position of the jacks, and as the oil-pump supplied oil at only a slow rate, being designed for pressure rather than speed, this jack-lifting operation consumed considerable time, before even the brake-shoes came into contact with the brake-ring for the purpose of lifting the same.

After the completion of the inspection and servicing operations, the rotor-member had to be slowly lowered until its runner rested on the thrust-bearing shoes, and this had to be done slowly so that the great weight of the rotor-member would not fall upon the runner with a blow. This required the manual manipulation of a needle-type exhaust-valve, to let the oil flow out of the hydraulic jacks at a very slow rate, until the weight of the rotor-member had been taken over by the runner, after which the exhaust-valve could be opened wide to let the brake-shoes fall away from the brake-ring as rapidly as possible. Finally, the oil had to be flushed out of the hydraulic jacks with air, so that the system would be in readiness for a braking-operation. After the workmen had assured themselves that everything was in proper shape, they had to climb away from the machine, in order to finally clear the machine for the next operation after the jacking operation.

The object of our invention is not only to make certain improvements in these braking and jacking operations of the braking and jacking means, but also to make it possible to utilize the same braking and jacking means to quickly and automatically (or semi-automatically) perform a pre-lubricating operation, in which the jacks are used, at the end of a period of shutdown of the generator, to momentarily lift the rotor-member so that its runner is raised slightly out of contact with the thrust-bearing shoes, and then lowered again, so that a film of oil would be trapped between the runner and the thrust-bearing shoes. This film will not become pressed out, from between the runner and the shoes, for some considerable time, so that, if the generator is started up within, say, thirty minutes after the film-forming operation, the runner would be supported on a film of oil during the initial starting-operation. Our new prelubricating operation can be completed in something like two minutes, as contrasted with the thirty to forty-

five minutes which were required in the previously known jacking operations for inspecting and servicing the thrust-bearings.

Heretofore, many large horizontal-shaft electric motors have been provided with oil-pressure means, for applying oil, under pressure, under the journal, when starting, in order to reduce the starting-friction forces and keep the current-inrush to a minimum. This feature has greatly reduced the strain on the journal-bearings of such large horizontal-shaft motors. Oil-pressure starting is not necessary, on water-wheel generators, so far as the starting-friction is concerned, since a water-wheel generator has ample power available to brake away the bearing from standstill. Furthermore, the installation of means for applying oil, under pressure, to each of the several tilting pads or thrust-bearing shoes is much too complicated for very general use in vertical-shaft machines, although it has been done on a few vertical-shaft motors where a low starting-torque is required.

The effect of the application of oil, under pressure, to a bearing-surface, as a preliminary to starting the supported machine after a period of shutdown, is, of course, to provide an oil-film on which the bearing-surfaces can ride, until the attainment of a speed which is sufficiently high for the surfaces to drag and maintain an oil-film under them, by reason of the oil-dragging effect of the relatively moving surfaces. Very much the same effect can be obtained by momentarily separating the opposed bearing-surfaces, so that they can be flushed with oil, after which enough oil remains, after the surfaces are brought together again, to provide an adequate oil-film for starting-purposes, if the machine is started immediately thereafter. Heretofore, the only available lifting-means, which could be used for establishing a prestarting oil-film on the bearing-surfaces of vertical-shaft generators, was the previously described slow and tedious jacking operation, which was so slow and tedious that it was practically out of the question, and out of proportion to its importance, so that it was not generally used or even proposed by anyone prior to ourselves, so far as we are aware.

The pivoted-pad thrust-bearing has an excellent record of reliability, with a great many years of service, when the bearing is properly installed, lubricated, and maintained. At the normal operating-speed, the bearing-surfaces are separated by a film of clean oil, and there is no wear. The only wear occurs during the starting and stopping periods, and more particularly during the starting-periods. During the starting-period if our present invention is not used, the bearing-runner is not carried on an oil-film until a speed of twenty to thirty R. P. M. is reached, or even until a still higher speed is reached, if the oil is hot or of poor oiliness, or if the bearing-surfaces are not sufficiently smooth and true. The smoothness of the bearing-surfaces and the oiliness of the lubricant both appreciably improve with time.

When a water-wheel generator is first placed in service, it requires certain dry-out treatments during which the machine may be submitted to many starts at high temperatures, thus imposing a particularly heavy duty on the bearings at a time when they are least able to withstand this duty. Our present invention is particularly applicable to the first fifty or one-hundred starts of a water-wheel generator, but our present invention is so simple that its use is probably justi-

fied, throughout the life of the generator, after any considerable period of shutdown.

More specifically stated, certain objects of our invention include the provision of means for using the brake-pressure air to pressurize the oil or other liquid for the hydraulic jacks, and to use this pressurized liquid to reduce the time necessary to elevate the jacks to the point where the brake-shoes engage the brake as a preliminary to the rotor-lifting operations, as well as utilizing the pressurized liquid to fill the hydraulic jacks during the braking-operation, so that the hydraulic jacks are always filled with oil or other liquid, as distinguished from air.

Still further objects of our invention are to provide two separate piping-connections, in addition to the pump-connection, between the hydraulic jacks and the liquid-reservoir, one of these piping-connections including a flow-limiting means which limits the return-liquid flow without requiring a minute adjustment of a valve for this purpose, while the other piping-connection is utilized to provide the necessary fast liquid-flow, either to or from the jack-cylinders, during different portions of the operations, as will be subsequently described.

A still further object of our invention is to provide an adequate system of signal-lights, whereby the condition of the braking and jacking apparatus is indicated at all times.

With the foregoing and other objects in view, our invention consists in the systems, combinations, apparatus, parts, and methods of design and operation, hereinafter described and claimed, and illustrated in the accompanying drawing, wherein:

Figure 1 is a much simplified, and somewhat diagrammatic, cross-sectional view of half of a water-wheel generator embodying our invention; and

Fig. 2 is a simplified diagrammatic view of the hydraulic system, and a simplified schematic diagram of an exemplary electrical system, embodying our invention.

As shown in Figure 1, the vertical-shaft rotating machine to which our invention is applicable may be a large water-wheel generator having a stator-member 1 and a rotor-member 2. In the illustrated type of machine, the rotor-member is suspended from its top, by means of a thrust-bearing which comprises a runner 4, carried by the rotor-member, a plurality of thrust-bearing shoes 5, carried by the stator-member and engaging the runner, and an oil-chamber 6 for lubricating-oil 7, in which said thrust-bearing shoes and at least the lower surface of the runner are immersed. Upper and lower guide-bearings 8 and 9 are also used, for positioning the rotor-member 2.

A braking and jacking equipment is also provided, near the lower periphery of the rotor-member 2, comprising a brake-ring 11, carried by the rotor-member, and a plurality of hydraulic jacks or brake-cylinders BC1 to BC8, carried by the stator-member and having brake-shoes 13, on their tops, in a position to engage the brake-ring 11, in an elevated position of the jacks or brake-pistons 14. Only one of the hydraulic jacks or brake-cylinders BC1 is shown in the diagrammatic sectional view of Fig. 1; all eight of them are shown, however, in the diagrammatic hydraulic-system representation in Fig. 2.

In accordance with our invention, we provide a hydraulic system which is diagrammatically represented in the upper portion of Fig. 2. An

air-tight oil-reservoir 16 is provided, containing a supply of oil or other liquid 17 for operating the hydraulic jacks. We also utilize an air-supply means, which is diagrammatically represented by an air-supply pipe 18, which is associated with air-piping 19, for supplying air to the oil-reservoir 16 at a relatively low pressure, such as 100 p. s. i., which is suitable for forcing oil into the hydraulic jacks or brake-cylinders BC1 and BC8 for pressing up the brake-shoes 13 with a force suitable for braking the rotor-member 2, but not nearly sufficient to lift said rotor-member.

We also utilize a high-pressure liquid-pump P (Fig. 2), which is included in a liquid-conducting pipe-connection 21 between said reservoir 16 and said hydraulic jacks or brake-cylinders BC1 to BC8, the pump P being operated to force liquid, at a relatively slow rate, but capable of producing a very high liquid-pressure, say, 2000 p. s. i., when the flow of liquid is restrained, thus pressing up the brake-shoes 13 (Fig. 1), with a force sufficient to lift the rotor-member 2, so that the bearing-runner 4 lifts up away from the thrust-bearing shoes 5. The pump P, as shown in Fig. 2, is provided with a suitable motive-means, illustrated as a three-phase motor M, the energization of which is controlled by a contactor-switch CS.

In addition to the pump-connection 21, we provide at least two other different liquid-conducting pipe-connections between the reservoir 16 and the hydraulic jacks or brake-cylinders BC1 to BC8. These liquid-conducting connections include a slow-flow connection 22, which includes a flow-control means or fixed flow-resistance 22R for providing for only a slow liquid-flow suitable for gently lowering the bearing-runner 4 (Fig. 1) onto the thrust-bearing shoes 5, after a lifting-operation. The liquid-conducting connections between the reservoir and the jacks also include a fast-flow connection 23, for providing for a fast-flow of liquid, in either direction, at different times during the operation of our equipment, as will be subsequently described.

Our braking and jacking equipment (Fig. 2) also includes various valves, such as a normally closed valve V1 in the slow-flow connection 22, which is provided with power-operated opening-means, shown, in Fig. 2, as an electromagnet or solenoid-coil, which can be properly identified by designating it with the same letter-designation, V1, which is applied to the valve as a whole.

We also utilize a specially constructed check-valve V2, in the fast-flow connection 23. It is provided with a ball 24, which, in its checking position, closes on a valve-seat 25 so as to prevent liquid-flow in the "releasing" direction, that is, from the hydraulic jacks to the oil-reservoir 16. The check-valve V2 is provided, however, with a special operating-pin 26, which is illustrated as being pressed upwardly, against the underside of the ball 24, by a compression-spring 27, so as to tend to open the valve. The valve-opening pressure of the spring 27 may be counteracted and overcome by a suitable power-energized operating-means, illustrated as an electromagnet or solenoid-coil which can be properly identified by the same letter-designation, V2, which is applied to the valve as a whole. The valve-opening spring 27 applies an opening-pressure which is sufficient to open the check-valve V2 against an oil-pressure equivalent to the air-pressure of the air-supply means 18, but not sufficient to open said check-valve against a liquid-pressure high

enough to cause the jacks to raise the rotor-member.

We also provide an air-valve V3, which is included in the air-piping 19, and which is normally set to exhaust air from the reservoir 16 to the atmosphere, at 28, as shown. The air-valve V3 is provided with power-energized opening-means for setting this valve so as to supply air to the reservoir 16 from the air-supply source or pipe 18, this opening-means being illustrated in the form of an electromagnet or solenoid-coil which is properly identifiable by means of the same letter-designation, V3, which identifies the air-valve as a whole. In order to provide a source of braking-energy in the event of a failure of the electrical or other power-means for actuating the air-valve V3, we preferably provide, also, a hand-operated valve V4, connected in parallel with the power-operated valve V3, so that air can be supplied to the oil-reservoir 16 by the hand-operated valve, if necessary.

It should be understood, of course, that the slow-flow valve V1 is biased to return automatically to its closed position, when it is deenergized, and that the air-valve V3 is biased to return automatically to its "exhaust" setting or position when deenergized.

We also provide, as a safety-measure, a relief-valve V5 for limiting the pressure which can be built up in the oil-reservoir 16, said limiting pressure being slightly above the air-pressure.

We also provide suitable means, illustrated in the form of check-valve V-CK, in the pump-connection 21 (Fig. 2), for preventing a reverse-flow of oil, in the "releasing" direction, from the jacks to the oil-reservoir 16. This makes it possible for the workman, in the "jacking" operation, as subsequently described, to shut off the pump-motor M when the bearing-runner 4 (Fig. 1) has been raised a desired amount, in which case, the pump-connection check-valve V-CK will hold the high-pressure oil in the hydraulic jacks or brake-cylinders BC1 to BC8 long enough for the insertion of suitable blocks (not shown) for supporting the weight of the rotor-member 2.

We also utilize various indicating or measuring devices for automatically responding to the positions or conditions of various parts of the equipment.

Thus, in the hydraulic system which is shown diagrammatically in Fig. 2, are included a plurality of brake-limit switches BL1 to BL8, associated with the several hydraulic jacks or brake-cylinders BC1 to BC8, to close when the brake-pistons are near their lowermost positions, say, within one-fourth of an inch of their lowest positions, assuming a one-half-inch brake-travel from the lowermost position to a point where the brake-shoes 13, in Fig. 1, engage the brake-ring 11.

As is shown in Fig. 2, we also provide an oil-pressure switch PS, which closes a make-contact PS, whenever the oil-pressure in the hydraulic jacks or brake-cylinders increases to a predetermined value which is intermediate between the braking-pressure of the air-supply 18 and the lifting-pressure which is necessary to actually lift the rotor-member 2 in Fig. 1. The pressure-contact PS is thus closed when the rotor-member 2 is lifted. When the rotor-member has been lowered to its normal position, in which the bearing-runner 4 rests on the thrust-bearing shoes 5, the high lifting-pressure of, say, 2000 p. s. i., in the hydraulic jacks or brake-cylinders BC1 to BC8 in Fig. 2, quickly drops, as the oil

continues to be drained or "released" from the jacks. When this oil-pressure is lowered to a value of say 250 p. s. i., the spring-pressure of the opening-spring 27 of the fast-flow check-valve V2 overcomes the oil-pressure and opens this check-valve V2; thus thereafter very quickly draining the oil out of the hydraulic jacks or brake-cylinders BC1 to BC8. At an oil pressure of say 200 p. s. i., while this oil is draining, the pressure-switch contact PS drops open, performing a control-switch function which will be subsequently described. The oil-pressure at which the pressure-switch contact PS is made may be of the order of 300 p. s. i.

All of the hydraulic equipment which is shown in Fig. 2, except the hydraulic jacks or braking-cylinders BC1 to BC8, and the two air-valves V3 and V4, is, or may be, mounted in the pit underneath the generator, on a suitable platform 31, as diagrammatically indicated by a rectangle 32 in Fig. 1, this pit-mounted equipment being indicated in Fig. 2 by a dotted-line enclosure 32.

As shown at the top of Fig. 1, the generator is provided with two underspeed switches, US—0 and US—.5, which close their respective contacts when the speed of the rotor-member 2 drops to or below the values for which the respective switches are set. The underspeed switch US—0 is a zero-speed switch, which closes its contact US—0 when the generator is substantially at standstill. The underspeed switch US—.5 is a half-speed switch, which closes its contact US—.5 when the speed of the generator slows down, during the stopping-operation, to half-speed or to some other predetermined speed intermediate between the full-speed and standstill.

As shown at an intermediate point on the generator-shaft 33 in Fig. 1, the generator is also provided, in accordance with our invention, with three upper-limit switches UL—.3, UL—.7 and UL—.8, which control their respective contacts, with a snap-action, when the rotor rises more than the respective amounts for which the several limit-switches are set, above the normal operating rotor-position in which the bearing-runner 4 rests on the thrust-bearing shoes 5. The first upper-limit switch UL—.3 opens a back-contact 29 and closes a make-contact 30 when the rotor rises .3 inch, or other similar value (but frequently less than this), or any value suitable for making sure that lubricating oil 7 has flowed over the tops of all of the thrust-bearing shoes 5. The second limit-switch UL—.7 opens at a .7-inch rise of the rotor, or other value convenient for the serviceman who has to inspect or service the thrust-bearing. The third limit-switch UL—.8 is a safety-switch for operating if either of the other two upper-limit switches should fail to operate, this safety-switch opening its contact UL—.8 at a .8-inch rise of the rotor.

In the illustrated form of embodiment of our invention, as shown more particularly in the central and lower portions of Fig. 2, we provide electrical control-equipment for our apparatus. We have illustrated a pushbutton control-system, utilizing two control-panels. One control-panel 35 carries a two-position lift-switch pushbutton LS, for controlling the lift-operation for the automatic or semi-automatic prelubricating process, and a two-position brake-switch pushbutton BS, for controlling the braking-operation. This control-panel 35 is (or may be) mounted to stand on the floor 36 of the generating station, as shown in Fig. 1. The control-panel 35 also carries the hand-operated emergency air-valve V4, as indi-

cated in Fig. 11. The automatic air-valve V3 is, or may conveniently be, mounted on the back of the control-panel 35, close to the emergency-air-valve V4, in a position which does not show in Fig. 1.

On, or associated with, the control-panel 35 is also an indicator panel 35', which carries an amber indicator-light A, three red indicator-lights B, three green indicator-lights G, and suitable legends therefor, as will be subsequently described.

A second control-panel 37 of Fig. 2 is a jacking-panel, which is preferably mounted, as shown in Fig. 1, in the under part of the generator, on a platform 38 on which the workman stands when he is in a position to watch or inspect the hydraulic jacks or brake-cylinders BC1 to BC8. This jacking-panel carries a two-position key-controlled button KB—J, for controlling the use of the jacking station or panel 37, a two-position "jacking" pushbutton JB—J, for controlling the jacking-operation, and a two-position "releasing" pushbutton JR—J, for releasing the high-pressure oil and lowering the rotor-member at the completion of the use of the jacking equipment.

As shown in Fig. 2, exemplary electrical connections are shown by schematic or "across-the-line" diagram. The various electrically operated relays, which are used, are each given a distinctive letter-designation, the same letter-designation being applied to the operating-coil and to all of the contacts of each relay, as a convention for indicating the cooperative relationship between the various parts of each relay. In addition, the connections between the various separated parts of each relay are further indicated diagrammatically by arrows or dotted lines, as a further convention for illustrating the mechanical connections between the various relay-coils and their associated contacts. All of the switches and relays are shown in their de-energized positions.

In Fig. 2, the first line or circuit 40 of the schematic connections indicates the energization of an auxiliary key-controlled relay XK in the "on" position of the key-controlled pushbutton KB—J at the jacking station. The second line, 44, of the schematic connections in Fig. 2 shows the use of the "on" position of the brake-switch pushbutton BS to energize the operating-coil of an auxiliary braking-relay XB from the positive bus (+), in series with a back-contact XL of an auxiliary lifting-relay XL, a circuit-conductor 42, and a back-contact XK of the auxiliary key-controlled relay XK, and thence to the negative bus (-).

The third line, 44, of the schematic connections in Fig. 2 shows the use of the zero-speed underspeed switch US—0 to energize a conductor 45, from the positive terminal (+) of a direct-current relay-source. The conductor 45 is used, in series with the "on" position of the lift-switch pushbutton-switch LS, to energize the operating-coil XL of the auxiliary lifting-relay XL, in series with a back-contact XB of the auxiliary braking-relay XB, this energizing-circuit being completed at the previously mentioned conductor 42.

The conductor 45 is also used, in a branch-circuit 45', to energize the two parallel-connected coils CS and X1, in series with the safety limit-switch UL—.8, a conductor 46, a back-contact XL, a conductor 47, and the back-contact 29 of the first upper-limit switch UL—.3, and thence to the previously mentioned conductor 42. The operating-coil CS actuates the previously men-

tioned contactor-switch CS and causes a closure of the three contactor-switch contacts CS in the energizing-circuit for the pump-motor M, as shown in the panel 32 at the top of Fig. 2. The operating-coil X1 is the coil of an auxiliary relay X1 which will be subsequently referred to.

The energizing-circuit for the parallel-connected operating-coils CS and X1 may also be completed, from the conductor 46, through a branch-circuit 48', which continues on, through the "on" position of the jacking pushbutton JB-J, and the upper-limit contact UL-1, to a conductor 48, and thence on through a make-contact XK, to the negative terminal (-) of the direct-current relaying-source.

The fourth and fifth lines of the schematic connections in Fig. 2 show two parallel-connected make-contacts XL and XB utilized to energize a conductor 62 from the positive bus (+), and this conductor is connected in series with the half-speed switch US-S, and the operating-coil V8 of the air-switch V8, the circuit of which is completed at the previously mentioned conductor 42.

The sixth line 53 of the schematic connections in Fig. 2 shows the use of the pressure-switch PS, in series with the operating-coil V1 of the slow-flow valve V1, to energize a conductor 54, which continues on, through two serially connected back-contacts XK and XL, to the previously mentioned conductor 42. The circuit from the conductor 54 also extends on, through a branch-circuit 54' and the "on" position of the releasing pushbutton RB-J, to the previously described circuit-conductor 48.

The seventh line, 56, of the schematic connections in Fig. 2 shows the energization of the amber indicator-lamp A, in series with the make-contact 38 of the first upper-limit switch UL-3, this energizing-circuit extending between the positive bus (+) and the aforesaid conductor 42.

The eighth line, 56, of the schematic connections in Fig. 2 shows the use of the eight brake-limit switches BL1 to BL8, connected in series between the positive bus (+) and a conductor 57, which continues on, through the operating-coil X2 of an auxiliary relay X2, the circuit of which is completed at the negative station-bus (-).

The conductor 57 is also utilized to energize the positive terminal 57' of the three green indicator-lights G, for indicating a "brakes down" condition during a lifting-operation, a brake-operation, and jack-operation, respectively. The lift-operation green light G has its negative circuit 58 completed, in series with a back-contact XB, which is connected to the previously described conductor 47. The brake-operation green light G has its negative circuit 58 completed through a back-contact XL, which is connected to the aforesaid conductor 47. The jack-operation green light G has its negative circuit 60 connected to the previously mentioned conductor 48.

The ninth line, 61, of the schematic connections in Fig. 2 shows the use of a back-contact X2 to energize the positive terminal 62 of the three "brakes up" red signal-lights R, the negative circuits of which are connected to the previously described green-light negative-circuits 58, 59 and 60, respectively, which are energized so as to indicate a lift-operation, a brake-operation, and a jack-operation, respectively.

The last two direct-current circuits of Fig. 2 show the use of two parallel-connected make-

contacts X2 and X1 to energize the operating coil V2 of the special fast-flow check-valve V2.

The operation of our invention may be summarized as follows.

Our invention makes it possible for the braking-system, or the braking and jacking means, of a vertical-shaft water-wheel generator, to perform any one of the three required functions of lifting, braking and jacking.

The lifting-operation is a prelubricating operation in which the rotor 2 is raised approximately one-quarter of an inch, by means of the brakes or jacks, and the rotor is then lowered, before starting the machine. This permits the formation of an oil-film between the thrust-bearing shoes 5 and the runner 4. If the machine is started immediately thereafter, or say within half an hour, this prelubricating film will be present, at the very first instant of starting, thus decreasing the possibility of bearing-damage or bearing-failure, and also reducing the required starting-torque.

During the braking-operation, the brake-shoes 13 are pressed against the brake-ring 11 under a relatively small oil-pressure which is maintained by the air-supply means or pipe 18. The brakes are commonly applied after the rotor-member has slowed down, of its own accord, to about half-speed, during a stopping-operation. The brakes stop the rotation of the rotor in a short period of time, thus avoiding prolonged bearing-surface damage, as a result of poor lubrication at slow speeds. After the generator has stopped, the brake-shoes are usually left applied, in order to prevent further rotation as a result of gate-leakage in the control of the water-wheel or turbine (not shown), to which the generator is connected.

The jacking-operation permits raising the motor seven-tenths to three-quarters of an inch, or any desired smaller amount, to facilitate repairs and inspection of the thrust-bearing.

Before examining in detail the several operations of lifting, braking and jacking, it is desirable to note that certain operations are automatic, or inherent in the oil-pressure conditions which are prevailing in the brake-cylinders, or inherent in the brake-position or in the setting of the several brake-limit switches BL1 to BL8, which are closed when the several hydraulic jacks or brake-pistons 14 are near their lowermost positions, or not more than, say, one-quarter of an inch above their lowest possible positions. In our braking system, or our braking and jacking means, the brakes or jacks never return altogether to their lowermost positions, but they are always filled with oil, and locked or retained in this oil-filled condition by the operation of the brake-limit switches BL1 to BL8, which are closed when the brakes are down as far as they are expected to go, in our system, thus normally energizing the operating-coil of the auxiliary relay X2, which, in turn, keeps its make-contact closed, in the energizing-circuit of the restraining or closing coil V2 of the special fast-flow check-valve V2, causing this valve to resume its normal check-valve function wherein it shuts off against liquid-flow in the "releasing" direction, that is, in the direction from the jacks to the oil-reservoir 16.

Another automatic function which is inherent in the apparatus is the pressure-switch control of the slow-flow valve V1. This valve is normally in its closed position, and it can not be opened except when the pressure-responsive switch PS

11

is closed. This pressure-switch PS does not close its contact until the oil-pressure in the brake-cylinders is considerably higher than the braking-pressure, so that the slow-flow valve V1 can not ever be opened during the braking operation, or during any other time except when the brake-shoes 13 are in contact with the brake-ring 11 and when the oil-pressure in the brake-cylinders has increased considerably above the pressure which is used for braking purposes, and is in fact approaching toward the pressures which are required for sustaining the weight of the rotor-member 2.

During the pressure-decreasing time, after the rotor has been lowered back to its normal position in which its weight is carried by the bearing-runner 4 resting on the thrust-bearing shoes 5, the pressure-responsive switch PS does not open its contact until a certain reduced pressure has been reached, say, 200 p. s. i., which is lower than the pressure which was required to close the PS switch-contact.

In detail, the method whereby the several operations of lifting, braking, and jacking are performed, by our semi-automatic apparatus, is as follows.

Only one of these operations can be performed at a time. When a jacking operation is to be performed, requiring that men climb in under the machine, the key-controlled pushbutton KB-J must be operated, at the jacking station, and when this is done, the auxiliary key-controlled relay XK picks up and disconnects the circuit 42 from the negative bus (-), thus "killing" the lift-controlling and brake-controlling operations, and also deenergizing the red and green lights R and G which are associated with said lifting and braking operations. At the same time, the make-contact XK of the auxiliary key-controlled relay XK energizes the circuit 43 from the negative bus (-), and makes it possible for the jacking button JB-J or the releasing button RB-J to be effectually operated, and also makes it possible for the jack-operation red and green lights to be energized.

At the same time, also, another back-contact XK, which is connected to the circuit 54, prevents the possibility of an unwanted "sneak" circuit when the auxiliary key-controlled relay XK is energized.

The lifting and jacking operations are also mutually exclusive of each other. When the auxiliary lifting-relay XL is energized, it opens back-contacts XL which "kill" the energizing-circuits for the auxiliary braking-relay XB, and the negative terminal 59 of the brake-operation lights R and G. In like manner, when the auxiliary braking-relay XB is energized, the corresponding lifting-operation circuits are "killed."

The lifting part of the prelubricating operation is performed by depressing the lift-switch pushbutton LS. If the generator is substantially at standstill, as it should be before this operation is undertaken the zero-speed switch US-0 will be closed, and the lifting button LS will energize the auxiliary lifting-relay XL, which closes its make-contact XL in the circuit 46-47 and thus energizes the CS-contactor which starts the motor M which is connected to the high-pressure oil-pump P. At the same time, the lifting-relay XL closes another make-contact XL in the circuit 52, thus energizing the air-valve V3 so as to set it to supply air to the oil-reservoir 16 at the normal braking-purpose air-pressure of say, 100 p. s. i. At the same time when the operating-coil of the contactor-switch CS is energized, the par-

12

allel-connected operating-coil of the auxiliary relay XI is energized, thereby picking up the make-contact XI and establishing an auxiliary holding-circuit for the restraining coil V2 of the specially constructed fast-flow check-valve V2, so that the valve-opening spring 27 will still be restrained; even after the hydraulic jacks or brake-pistons have started to move upwardly far enough to break one of the brake-limit contacts BL1 to BL8.

The energization of the pump-motor M, during the lifting-operation, starts the pump P, but the pumping-velocity of this pump is necessarily limited, because of its design to be operative against a heavy oil-pressure, which may be of the order of 2000 p. s. i., and said pump is designed to deliver oil at a relatively slow rate at these high pressures. When the back-pressure against the oil delivered by the pump is small, as will be the case until the brake-shoes 13 rise into engagement with the brake-ring 11, the flow-rate of the oil which is delivered by the pump P is nevertheless limited, so that it supplies oil at a relatively low rate. However, the admission of air, under pressure, to the oil-reservoir 16, and the inclusion of our fast-flow oil-supply connection 23 between the oil-reservoir 16 and the hydraulic cylinders BC1 to BC8, provide for a relatively fast flow of oil, at say, 100 p. s. i., through this fast-flow connection until the brake-shoes 13 are brought up into engagement with the brake-ring 11.

When the brake-shoes come into engagement with the brake-ring, the 100-pound oil stops flowing through the check-valve V2 in the fast-flow connection 23, and the oil-pump P begins to build up the high oil-pressure for which it is designed, automatically holding the fast-flow check-valve V2 closed, against the pressure of its opening-spring 27, in the fast-flow connection 23, so that oil is thereafter supplied to the brake-cylinders, exclusively by the pump P.

When the rotor-member has been raised a predetermined amount, corresponding to the setting of the first upper-limit switch UL-3, the back-contact of this switch opens, thus automatically deenergizing the oil-pump P. The de-energization of the pump-motor contactor-switch CS, by the operation of the upper-limit switch UL-3, also deenergizes the auxiliary relay XI, which opens its make-contact XI and deenergizes the restraining-winding V2 of the specially constructed first-flow check-valve V2. This de-energization of the restraining-winding V2 permits the valve-opening spring 27 of the valve V2 to apply its spring-pressure in a direction tending to open said valve, but this spring-pressure is much too low to overcome the high lifting-pressure of the order of 2000 p. s. i., which is now present on the brake-cylinder side of the check-valve. After the deenergization of the pump-motor contactor-switch CS by the limit-switch UL-3, the check-valve V-CK, in the pump-connection 21, retains the oil in the hydraulic jack or brake-cylinders BC1 to BC8, preventing the lowering of the rotor-member until the lifting pushbutton LS is moved to its "off" position.

The return of the lifting button LS to its "off" position completes the prelubricating operation by gently lowering the rotor-member so that the bearing-runner 4 comes gently down into contact with the thrust-bearing shoes 5, which are now coated with a film of oil. When the auxiliary lifting relay XL is deenergized by the "off" pos-

13

tion of the lifting button LS, its back-contact XL closes, in the circuit 54—42, and energizes the operating-coil V1 of the slow-flow valve V1, thus opening said valve, this operation being possible because the pressure-responsive switch PS is now closed. At the same time, the deenergization of the auxiliary lifting relay XL opens its make-contact XL in the circuit 52, and thus deenergizes the air-valve V3, which automatically returns to its setting in which it exhausts air from the oil-tank 16 to the atmosphere.

Oil thereupon flows through the slow-flow connection 22, in the "releasing" direction, that is, from the hydraulic jacks or brake-cylinders to the oil-reservoir 16, and this operation continues until the bearing-runner 4 comes gently to rest on the thrust-bearing shoes 5. As soon as this happens, the oil-pressure quickly relieves itself, in the hydraulic jacks, because the oil is continuing to escape or flow out, through the slow-flow valve V1. When the oil-pressure in the hydraulic jacks is reduced to a predetermined intermediate value, say, 250 p. s. i. intermediate between the lifting-pressure of say 2000 p. s. i. and the braking-pressure of say 100 p. s. i., the valve-opening spring 27, of the fast-flow check-valve V2 overcomes the pressure of the oil in the hydraulic jacks or brake-cylinders, thus opening said valve V2, and thus providing a fast-flow connection which quickly drains the oil out of the brake-cylinders. Almost immediately after the opening of the fast-flow valve V2, the pressure-switch PS opens, at say 200 p. s. i., thus deenergizing the slow-flow valve V1 and causing it to close.

The draining of oil from the brake-cylinders continues until the brake-cylinders have been returned to a sufficiently low position to reclose all of the brake-limit switches BL1 to BL8, which thereupon energize the auxiliary relay X2; and through its make-contact X2 the restraining or closing coil V2 is energized, which overpowers the valve-opening spring 27, and causes the valve V2 to return to its normal check-valve function, which checks any further return of oil from the brake-system to the oil reservoir 16. In this manner, oil is kept trapped in the brake-system at all times, so that it is always in readiness for hydraulic operation, by the application of oil-pressure, as distinguished from gas-operation, or operation in which considerable volumes of a compressible medium such as gas are entrapped.

For the braking-operation, the brake-switch pushbutton BS is depressed. This energizes the auxiliary braking-relay XB, the result of which is the closure of the make-contact XB in the energizing-circuit 52 of the air-valve V3. This energizing-circuit can not be completed, even though the auxiliary brake-relay XB is energized, unless and until the speed of the rotor-member 2 is less than half-speed or other intermediate speed for which the underspeed switch US—5 is set. This is for the purpose of preventing a brake-damaging application of the brakes when the rotor-member is going too fast. When the energizing-circuit 52 is closed by the simultaneous closure of the make-contact XB and the underspeed switch US—5, the operating-coil V3 of the air-valve is energized, thereby causing said air-valve to move to its setting in which air is delivered, under its constantly maintained 100-pounds pressure, to the oil-tank 16. This puts the oil 17 under the same 100-pounds pressure, and forces the oil through the check-valve V2 in the fast-flow connection 23, thus

14

applying it directly to the brake-cylinders BC1 to BC8, and applying the brakes. The brakes remain applied as long as air-pressure continues to be supplied to the oil-reservoir 16.

At the very beginning of the application of the brakes, the restraining or closing coil V2 of the specially constructed fast-flow check-valve V2 is energized, so that the said valve V2 is closed, or in its normal check-valve condition which prevents liquid-flow in the "releasing" direction, that is, from the brake-cylinders to the oil-reservoir, while permitting oil-flow from the reservoir to the brake-cylinders. The air-pressure in the oil-reservoir 16 thus causes the oil 17 to flow in the direction which is permitted by the check-valve V2 thus flowing into the brake-cylinders and starting to raise the same. Almost immediately, these cylinders break their brake-limit contacts BL1 to BL8, and as soon as the first one of these contacts opens, the auxiliary relay X2 is deenergized, thus, in turn, deenergizing the restraining-coil V2 of the check-valve V2, thus causing the valve-opening spring 27 to open the check-valve wide, thus reducing the resistance to the flow of oil from the oil-reservoir 16 to the brake-cylinders BC1 to BC8, resulting in a fast application of the brakes.

To release the brakes, the brake-switch pushbutton BS is returned to its "off" position, the air-valve V3 is deenergized and returns to its normal setting in which air is exhausted from the oil-tank 16 to the atmosphere. This permits the oil to drain from the brake-cylinders to the oil-reservoir 16, because the restraining or closing coil V2 of the check-valve V2 is deenergized whenever the brake-shoes are in their braking position, and hence the valve-opening spring 27 keeps this valve V2 open, under these conditions, because the oil-pressure in the brake-shoes, during braking-conditions, is too small to keep the ball 24 of the valve V2 closed against the pressure of the spring 27. Oil thus drains quickly out of the brake-cylinders, permitting the brake-pistons 14 to lower until all eight of the brake-pistons have fallen sufficiently to close the eight brake-limit switches BL1 to BL8, whereupon the auxiliary relay X2 is again energized, and this again energizes the restraining or closing coil V2 of the check-valve V2, thus preventing further drainage of oil out of the brake-cylinders.

For the jacking-operation, the jacking-station 31 must be unlocked, through the use of the key-controlled pushbutton KB—J, which locks out, or renders ineffective, the lifting and braking buttons LS and BS, and sets up the circuit 48 which is necessary for energizing the jack-station jacking and release buttons JB—J and RB—J.

A jacking-operation is initiated by depressing the jacking button JB—J. If the rotor-member is substantially at standstill, the zero-speed switch US—0 will be closed, and the actuation of the jack-button JB—J will immediately energize the contactor-switch CS which energizes the pump-motor M. In many cases, as illustrated in the exemplary form of embodiment of our invention which is shown in the drawing, a fast elevation of the brake-shoes 13, up to the point where they come into contact with the brake-ring 11, is not desired, during the jacking-operation, because the workman at the jacking station can profitably employ the intervening time by inspecting the equipment which is visible at the jacking station. For this reason, we have not shown our jacking-button JB—J in a circuit which would result 70 in the simultaneous energization of the air-valve

V3 and the pump-motor contactor CS, as was done in the lifting part of the prelubricating operation, where a quick operating-time was quite important. We wish it to be understood, however, that the assistance of the air-supply could be had, in the jacking-operation, as well as in the lifting-operation, if desired.

It will be noted that the energization of the motor-controlling contactor switch CS in the jacking-operation is accompanied, as in the lifting-operation, by a simultaneous energization of the auxiliary relay X1, which closes its make-contact X1 in a holding circuit for making sure that the spring-restraining or closing-means of the fast-flow check-valve V2 is energized, thus insuring that the check-valve V2 will be in its normal check-valve condition for preventing a flow of liquid in the "releasing" direction, from the brake-cylinders to the oil-reservoir 16, while the oil-pump P is pumping oil into the brake-cylinders, through the pump-connection 21.

If the jack-station operator desires, he can shut off the pump-motor M, at any point during the lifting-operation, by returning the jacking push-button JB-J to its "off" position. If this is not done, the jacking operation will automatically continue until the limit-switch UL-3 opens, and deenergizes the pump-motor, at the desired upper limit of travel of the hydraulic jacks or brake-pistons 14. When the pump-motor is deenergized, at the end of a desired lifting-operation, the pump-connection check-valve V-CK prevents the immediate back-flow or escape of the liquid from the brake-cylinders to the oil-reservoir, through the pump-connection 21.

To lower the rotor-member after a jacking-operation, the releasing button RB-J may be depressed, or the key-controlled button KB-J may be returned to its "off" position. In either event, the slow-flow valve V1 will be energized, starting the same automatic releasing-cycle which has already been described, in connection with the lifting-cycle, whereby oil is first returned slowly, to the oil-chamber 16, until the weight of the rotor-member is taken over by the thrust-bearings, after which oil is quickly returned until the brake-pistons reach their desired lowered positions in which the brake-limit switches BL1 to BL8 are closed, whereupon the fast-flow check-valve V2 is restored to its normal check-valve function, retaining the entrapped oil in the brake-cylinders BC1 to BC8.

During all of these operations, the indicator-lamp panel 35' shows the position of the equipment at all stages, and it also shows which cycle of operation is being followed, whether lifting, braking, or jacking.

Thus, when the jack-station-responsive relay XB is deenergized, during the non-use of the jacking-panel 37, the XK back-contact energizes the circuit 42 and the XK make-contact deenergizes the circuit 48 and hence the jack-operation red and green lamps R and G. From the energized circuit 42, a selection is made, according to the position of the first upper-limit switch UL-3, to energize the circuit 47, and thence the negative terminals 58 and 59 of the lift-indicating and the brake-indicating lights R and G, if the rotor-member 2 is in its normal down-position, or if it has not been raised or lifted sufficiently to actuate the limit-switch UL-3. If, however, the rotor-member has been lifted enough to actuate the first limit-switch UL-3, the make-contact 30 of this switch energizes the amber light A from the circuit 42. The energization of the

amber light A, therefore, always indicates a raised position of the rotor-member 2, at a time when the jacking-station 37 is not being used, that is, at a time when either the lifting-button LS or the braking-button BS is depressed, but since the braking-button BS never results in lifting the rotor-member, as has been already described, a lighting of the amber light A always necessarily indicates an up-position of the rotor-member during a lifting-operation.

When the jacking-station 37 is in use, and its key-controlled pushbutton KB-J is depressed or turned on, the energization of the auxiliary jacking-starting relay XK will energize the circuit 48, as previously stated, and hence will energize the negative terminal 60 of the "jack" indicator-lights R and G.

When the jacking-station key-controlled pushbutton KB-J is not depressed, and the jacking-station auxiliary relay XK is therefore deenergized, and when the rotor-member is not in its up-position, then the back-contact 29 of the first limit-switch UL-3 will be closed and the circuit 47 will be energized, as has been stated; and the negative terminals 58 and 59 of the "lift" and "brake" indicator-lights R and G will both be energized whenever neither the lifting-button LS nor the braking-button BS is depressed. When either the lift-operation pushbutton LS or the brake-operation pushbutton BS is then depressed, it will pick up its corresponding auxiliary relay XL or XB, opening a back-contact XL in the negative circuit 59 of the "brake" lights, or opening a back-contact XB in the negative circuit 58 of the "lift" lights, as the case may be.

Only one of the pushbuttons LS, BS or KB-J can be effectually operated at any one time, and the energizing-circuits for the negative terminals of the three pairs of red and green indicator-lights are so controlled as to make possible the energization of the lights of only the particular red-and-green pair which is marked for indicating the corresponding operation, whether lifting, braking, or jacking.

Whether the red light or the green light is energized depends upon the position of the brake-pistons 14. When the brakes are down, the eight brake-limit switches BL1 to BL8 are all closed, and the positive circuit 57' of the green lights G is energized. At the same time, the auxiliary relay X2 is energized, from the circuit 57, and the back-contact X2 is thus open, in the circuit 61, so as to deenergize the positive terminal 62 of the red lights R.

As soon as any one of the three pushbuttons LS, BS and JB-J is effectually energized, the brake-pistons 14 will begin to rise, as has already been described, and as soon as one of the brake-limit switches BL1 to BL8 is opened, in response to this rising of the brake-pistons, the green-light circuit 57' will be deenergized, and the red-light circuit 62 will be energized, putting out the green light or lights which had been lit, and energizing the red light corresponding to the pair which indicates the lifting, braking, or jacking operation which is being performed at the moment.

In the normal condition of the indicator-lights, when none of the three operations is being performed with the braking and jacking equipment, the top two green lights, of the lift-operation and brake-operation pairs, are illuminated.

At the end of a period of shutdown, with the rotor-member 2 at standstill, if the station-operator desires to put the generator in use again, a prelubricating operation is initiated, by effectually energizing the lift-switch pushbutton LS,

which immediately puts out the second green light, in the "brake" pair, by reason of the opening of the back-contact **XL** in the light-circuit **59**. This leaves only the top green light **G** illuminated, but almost immediately, as the brakes first begin to rise, one or more of the brake-limit switches **BL1** to **BL8** opens, extinguishing the top green light **G** and illuminating the top red light **R**, of the "lift" pair of indicator-lights, thus indicating that the brakes are up, during a lifting-cycle, and that the generator is not in a safe condition for being started. When the rotor-member **2** of the generator is finally lifted, at the end of this lifting-operation, the first upper-limit switch **UL-3** not only deenergizes the pump-motor **M**, as previously explained, but simultaneously extinguishes the red lift-indicating lamp **R** and illuminates the amber lamp **A**, thus indicating that the rotor is up, during the lifting-cycle, and telling the station-operator that the rotor can be lowered again, as soon as he is ready to start the generator.

When the station-operator is ready, the lifting-button **LS** is moved to its "off" position, and the amber light **A** quickly goes out, as soon as the rotor-member is lowered far enough to return the limit-switch **UL-3** to its initial position. When this happens, the two top red lights **R**, in both the lift-indicating pair and the brake-indicating pair, are illuminated, because both of the pushbuttons **LS** and **BS** are now open. This condition continues until the brake-pistons **14** are in the lowest positions which are permitted, in our apparatus, at which time the closure of the eight brake-limit switches **BL1** to **BL8** will result in the extinguishment of the two top red lights **R** and the energization of the two top green lights **G**, thus informing the station-operator that a prelubricating film has been provided on the thrust-bearing shoes, and that the machine is therefore ready for immediate starting. The station-operator is then expected to start the water-wheel generator, and if he does this within a reasonable time, such as, within half an hour, there will be an adequate film on the thrust-bearing shoes to protect the thrust-bearing, and to keep down the required starting-torque, during the initial period of the starting of the rotor-member **2**. During the normal operation of the machine, the top two green lights **G** stay illuminated during the entire time.

When a braking-cycle is put into effect, by the depression of the braking-button **BS**, the top green light **G**, of the lift-indicating means, is immediately extinguished, by the opening of the back-contact **XB** in the light-circuit **58**. Nothing further happens unless or until the speed of the generator drops below the half-speed value or other value necessary to actuate the under-speed switch **US-5** in the control circuit **52**, whereupon the braking-cycle actually begins, and the brakes are activated. As soon as one or more of the brakes moves far enough to open its brake-limit switch, the brake-indicating green light **G** is extinguished and the brake-indicating red light **R** is illuminated, indicating that the brakes are on, or just going on. The brake-indicating red light **R** stays on, as long as the brakes are on, whether the rotor-member of the machine is being brought to standstill, or is being kept at standstill by the brakes.

When the brakes are to be released, the brake push-button **BS** is moved to its "off" position, and the auxiliary braking-relay **XB** is immediately deenergized, closing its back-contact **XB**

in the lighting-circuit **58** and causing the lift-indicating red light **R** to be illuminated, in addition to the brake-indicating red light **R**. The brakes immediately start their dropping-out operation, as has already been explained, and as soon as the brakes are down, the brake-limit switches **BL1** to **BL8** extinguish the top two red lights **R**, and illuminate the top two green lights **G**, indicating that the brakes are off.

During a jacking-operation, the two top pairs of lights are extinguished, by the actuation of the jack-station auxiliary relay **XK**, as already explained, and the bottom pair of indicator-lights **R** and **G** are placed in condition for operation. At first, however, only the jack-position green light **G** lights up, because the hydraulic jacks and the brake-shoes are at their lowermost positions contemplated in our apparatus, and the brake-limit switches **BL1** to **BL8** are closed.

When the jacking pushbutton **JB-J** is depressed, initiating oil-flow into the brake-cylinders, the brake-pistons begin to rise, and at the initial stages of this movement, as soon as one of the brake-limit switches **BL1** to **BL8** is opened, the green light **G** is extinguished, and the red light **R** is illuminated, in the jacking-indicating pair, which is the lowermost pair of the indicator-lights. The red indicator-light **R** thereupon remains lit, during the entire jacking-operation, regardless of the position of the rotor-member; and the red jack-indicating light **R** does not go out again until the conclusion of the releasing-operation, after the rotor-member has been let down again so that its bearing-runner **4** rests on the thrust-bearing shoes **5**, and after all of the brake-shoes have moved clear of the brake-ring **11**, and after the brake-shoes have actually reached the lowest position which is contemplated in our apparatus, at which time the closing of the eight brake-limit switches **BL1** to **BL8** extinguishes the red jack-indicating light and illuminates the green jack-indicating light.

When the workman is ready to leave the jacking station **37**, he returns the key-controlled pushbutton **KB-J** to its "off" position, thus de-energizing the auxiliary jack-station relay **XK**, and extinguishing the green jack-indicating-light **G**, at the circuit **60-48**, and illuminating the two top green indicating-lights, as previously explained.

While we have shown our invention in a single illustrative form of embodiment, intended to be illustrative of the general principles of the invention, we wish it to be clearly understood that we are not limited to this precise arrangement of apparatus.

It is obvious, for example, that the equipment could be made either less automatic than it is, with more of the operations under manual control, or more completely automatic, with relay-means for automatically carrying out the described sequences of operations, referring to both the operational sequences relating to the performance of the three essential operations of pre-lubricating, braking, and jacking, and also the operational control of the water-wheel generator itself.

For example, while we have explained that the station-engineer would perform a prelubricating operation before starting his generator, and would start his generator within thirty minutes (or other prescribed time) after the completion of the pre-lubricating operation, we wish it to be understood that these operations could be performed either manually or automatically, or that a starting of

the water-wheel generator could be absolutely prevented, by interlocks, unless the brakes are released and unless the prelubricating operation has been completed within the past half-hour.

It is also obvious that a suitable time-switch (not shown) could be utilized for putting out one or both of the two top green lights G if the station-engineer had not started the generator within the prescribed half-hour.

While we have shown a pushbutton type of control, utilizing two-position pushbuttons, it is also obvious that we could utilize pushbuttons which are momentarily depressed, not of the position-retaining type, but with suitable well-known relay holding-circuits for carrying through the prescribed automatic operations, once they are started; or we might not use pushbuttons at all, using hand-operated switches, instead.

We contemplate that the foregoing and other changes of substitution, omission and addition can be made, by those skilled in the art, without departing from the essential features of our invention, in its broadest aspects. We desire, therefore, that the appended claims shall be accorded the broadest construction consistent with their language.

We claim as our invention:

1. A vertical-shaft rotating machine having a stator-member and a rotor-member; a thrust-bearing, comprising a runner carried by the rotor-member, a plurality of thrust-bearing shoes carried by the stator-member and engaging the runner for supporting the weight of the rotor-member, and an oil-chamber for oil in which said thrust-bearing shoes and at least the lower surface of said runner are immersed; guide-bearing means for positioning the rotor-member; a braking and jacking means, comprising a brake-ring carried by the rotor-member, and a plurality of hydraulic jacks carried by the stator-member and having brake-shoes, on their tops, in a position to engage said brake-ring in an elevated position of said jacks; an air-tight liquid-reservoir for a liquid for operating said hydraulic jacks; an air-supply means, and associated air-piping, for supplying air to said reservoir at a relatively low pressure suitable for braking said rotor-member but not sufficient to lift said rotor-member; said air-piping including an air-valve which may be set to either supply air to said reservoir or to exhaust air from said reservoir to the atmosphere; and at least three different liquid-conducting piping-connections between said reservoir and said hydraulic jacks, said connections including: a pump-connection including a high-pressure liquid-pump, and motive-means for said pump, operable, at times, to supply liquid from said reservoir to said hydraulic jacks at a pressure sufficient to lift said rotor-member so that said runner is raised off of said thrust-bearing shoes; a slow-flow connection providing for only a slow liquid-flow suitable for gently lowering said runner onto said thrust-bearing shoes after a lifting-operation, said slow-flow connection including a valve; and a fast-flow connection providing for a relatively fast liquid-flow and including valve-means.

2. The invention as defined in claim 1, in combination with means for, at times, providing an automatic lifting-operation in which liquid is at first supplied, at a relatively rapid rate, from said reservoir, under air-pressure, through said fast-flow connection, to said hydraulic jacks, until said brake-shoes are brought up substantially into engagement with said brake-ring, and in which

liquid is then supplied, at a relatively slower rate, to said hydraulic jacks, exclusively through said pump-connection, with the pump operating, so as to raise said rotor-member.

3. The invention as defined in claim 1, characterized by said fast-flow valve-means being a check-valve which at times operates to check liquid-flow in the direction from the hydraulic jacks to the reservoir, in combination with control-means for at times causing said air-valve to be set to supply air to the reservoir, and also causing the motive-means for said pump to be operated.

4. The invention as defined in claim 1, characterized by said fast-flow valve-means being a check-valve which at times operates to check liquid-flow in the direction from the hydraulic jacks to the reservoir, in combination with automatically responsive control-means, operatively effective when the hydraulic jacks are near their lowermost positions, and also operatively effective when the motive-means for the pump is operating, for causing said fast-flow valve-means to operate as a normal check-valve, and automatically responsive control-means, operatively effective at other times, for applying, to said fast-flow check-valve, an unseating force which is sufficient to open said check-valve against a liquid-pressure equivalent to the air-pressure but not sufficient to open said check-valve against a liquid-pressure high enough to cause said jacks to raise said rotor-member.

5. The invention as defined in claim 1, in combination with means for, at times, providing an automatic lowering-operation in which liquid is at first caused to flow, at a relatively slow rate, through said slow-flow connection, from said jacks to said reservoir, until the liquid-pressure in the jacks drops below a value intermediate between the braking air-pressure and the rotor-lifting oil-pressure, and in which liquid is then caused to flow, at a relatively rapid rate, through said fast-flow connection, from said jacks to said reservoir.

6. The invention as defined in claim 1, characterized by said slow-flow valve and said fast-flow valve-means being normally in their closed positions, means operative, at times, to cause said slow-flow valve to open so as to lower said jacks, and pressure-responsive means, responsive to the liquid-pressure within said jacks, and operatively effective, at pressures below a value intermediate between the braking air-pressure and the rotor-lifting oil-pressure, for causing said fast-flow valve-means to be opened and causing said slow-flow valve to be reclosed.

7. The invention as defined in claim 1, characterized by said slow-flow valve being normally in its closed position and said fast-flow valve-means being a check-valve which at times operates to check liquid-flow in the direction from the hydraulic jacks to the reservoir, in combination with automatically responsive control-means, operatively effective when the hydraulic jacks are near their lowermost positions, and also operatively effective when the motive-means for the pump is operating, for causing said fast-flow valve-means to operate as a normal check-valve, automatically responsive control-means, operatively effective at other times, for applying, to said fast-flow check-valve, an unseating force which is sufficient to open said check-valve against a liquid-pressure equivalent to the air-pressure but not sufficient to open said check-valve against a liquid-pressure high enough to

cause said jacks to raise said rotor-member, means operative, at times, to cause said slow-flow valve to open so as to lower said jacks, and pressure-responsive means, responsive to the liquid-pressure within said jacks, and operatively effective, at pressure below a value intermediate between the braking air-pressure and the rotor-lifting oil-pressure, for causing said slow-flow valve to be closed if it was open, and for preventing said slow-flow valve from being opened if it is closed.

8. The invention as defined in claim 1, in combination with prelubricating means for establishing oil-films between the thrust-bearing shoes and the runner, preliminarily to starting the vertical-shaft rotating machine after a period of shutdown, said prelubricating means comprising a lift-operation control-means for providing an automatic lifting-operation in which liquid is at first supplied, at a relatively rapid rate, from said reservoir, under air-pressure, through said fast-flow connection, to said hydraulic jacks, until said brake-shoes are brought up substantially into engagement with said brake-ring, and in which liquid is then supplied, at a relatively slower rate, to said hydraulic jacks, exclusively through said pump-connection, with the pump operating, so as to raise said rotor-member; limit-means, associated with said lift-operation control-means, for limiting the amount by which the rotor-member can be lifted; and lowering means, associated with said lift-operation control-means, for providing an automatic lowering-operation in which liquid is at first caused to flow, at a relatively slow rate, through said slow-flow connection, from said jacks to said reservoir, until the liquid-pressure in the jacks drops below a value intermediate between the braking air-pressure and the rotor-lifting oil-pressure, and in which liquid is then caused to flow, at a relatively rapid rate, through said fast-flow connection, from said jacks to said reservoir.

9. The invention as defined in claim 1, in combination with prelubricating means for establishing oil-films between the thrust-bearing shoes and the runner, preliminarily to starting the vertical-shaft rotating machine after a period of shutdown, said prelubricating means having a "lift" position and a "release" position; said prelubricating means, in its "lift" position, being operative to set up operating-conditions in which said slow-flow valve is closed, said air-valve is set to supply air to the reservoir, said motive-means for the pump is in operation, and said fast-flow valve-means is under such control as to at first permit liquid to flow through said valve-means, during relatively low-pressure oil-conditions, in the direction from said reservoir to said hydraulic jacks, until the brake-shoes are brought up substantially into engagement with the brake-ring, and then to prevent liquid from flowing through said valve-means in the reverse direction as the oil-pump develops an oil-pressure in excess of the air-pressure; limit-means for automatically stopping the motive-means for the pump in response to a predetermined lift of the rotor-member; and said prelubricating means, in its "release" position, being operative to set up operating-conditions in which said motive-means for the pump is off, said air-valve is set to exhaust air from the reservoir, said slow-flow valve is under such control as to be open at first, while the rotor-member is slowly lowering, and then to be closed subsequent to the resting of the runner on the thrust-bearing shoes, and said fast-flow

valve-means is under such control as to at first prevent liquid-flow through said valve-means in the "releasing" direction from said jacks to said reservoir under the high-pressure conditions existing while the jacks are supporting the weight of the rotor-member, and then to permit liquid-flow through said valve-means in said "releasing" direction subsequent to the resting of the runner on the thrust-bearing shoes.

10. The invention as defined in claim 1, characterized by said slow-flow valve being normally in its closed position, and said fast-flow valve-means being a check-valve which at times operates to check liquid-flow in the direction from the hydraulic jacks to the reservoir, in combination with prelubricating means for establishing oil-films between the thrust-bearing shoes and the runner, preliminarily to starting the vertical-shaft rotating machine after a period of shutdown, said prelubricating means comprising a lift-operation control-means for causing said air-valve to be set to supply air to the reservoir, and also causing the motive-means for said pump to be operated, limit-means for automatically stopping the motive-means for the pump in response to a predetermined lift of the rotor-member, lowering-means for causing said air-valve to be set to exhaust air from the reservoir, and also causing said slow-flow valve to open, and pressure-responsive means, responsive to the liquid-pressure within said jacks, and operatively effective, at pressures below a value intermediate between the braking air-pressure and the rotor-lifting oil-pressure, for causing said fast-flow valve-means to be opened and causing said slow-flow valve to be reclosed.

11. The invention as defined in claim 1, characterized by said slow-flow valve being normally in its closed position, and said fast-flow valve-means being a check-valve which at times operates to check liquid-flow in the direction from the hydraulic jacks to the reservoir, in combination with automatically responsive control-means, operatively effective when the hydraulic jacks are near their lowermost positions, and also operatively effective when the motive-means for the pump is operating, for causing said fast-flow valve-means to operate as a normal check-valve, automatically responsive control-means, operatively effective at other times, for applying, to said fast-flow check-valve, an unseating force which is sufficient to open said check-valve against a liquid-pressure equivalent to the air-pressure but not sufficient to open said check-valve against a liquid-pressure high enough to cause said jacks to raise said rotor-member, prelubricating means for establishing oil-films between the thrust-bearing shoes and the runner, preliminarily to starting the vertical-shaft rotating machine after a period of shutdown, said prelubricating means comprising a lift-operation control-means for causing said air-valve to be set to supply air to the reservoir, and also causing the motive-means for said pump to be operated, limit means for automatically stopping the motive-means for the pump in response to a predetermined lift of the rotor-member, and lowering-means for causing said air-valve to be set to exhaust air from the reservoir, and also causing said slow-flow valve to open.

12. The invention as defined in claim 1, in combination with means for, at times, providing a braking-operation in which liquid is supplied from said reservoir, under air-pressure alone, through said fast-flow connection, to said hydraulic jacks.

13. The invention as defined in claim 1, in combination with brake-operation control-means having an "on" position and an "off" position; said brake-operation control-means, in its "on" position, being operative to set up operating-conditions in which the slow-flow valve is closed, the motive-means for the pump is off, the air-valve is set to supply air to the reservoir, and the fast-flow valve-means is under such control as to permit liquid-flow through said valve-means in the direction from the reservoir to the jacks; and said brake-operation control-means, in its "off" position, being operative to set up operating-conditions in which the slow-flow valve is closed, the motive-means for the pump is off, the air-valve is set to exhaust air from the reservoir, and the fast-flow valve-means is under such control as to permit liquid-flow through said valve-means in the "releasing" direction from the jacks to the reservoir.

14. The invention as defined in claim 1, characterized by said slow-flow valve being normally in its closed position, and said fast-flow valve-means being a check-valve which at time operates to check liquid-flow in the direction from the hydraulic jacks to the reservoir, in combination with automatically responsive control-means, operatively effective when the hydraulic jacks are near their lowermost positions, and also operatively effective when the motive-means for the pump is operating, for causing said fast-flow valve-means to operate as a normal check-valve, automatically responsive control-means, operatively effective at other times, for applying, to said fast-flow check-valve, an unseating force which is sufficient to open said check-valve against a liquid-pressure equivalent to the air-pressure but not sufficient to open said check-valve against a liquid-pressure high enough to cause said jacks to raise said rotor-member, and brake-operation control-means having an "on" position and an "off" position; said brake-operation control-means, in its "on" position, being operative to cause said air-valve to be set to supply air to the reservoir, whereby liquid is supplied from said reservoir, under air-pressure alone, through said fast-flow connection, to said hydraulic jacks; and said brake-operation control-means, in its "off" position, being operative to cause said air-valve to be set to exhaust air from the reservoir.

15. The invention as defined in claim 1, in combination with jack-operation control-means having a "jack" controller and a "release" controller; said "jack" controller, in its "on" position, being operative to set up operating-conditions in which the air-valve is set to exhaust air from the reservoir, the slow-flow valve and the fast-flow valve-means are closed, and the motive-means for the pump is in operation; limit-means for automatically stopping the motive-means for the pump in response to a predetermined lift of the rotor-member; said "jack" controller, in its "off" position, being operative to immediately stop the motive-means for the pump; and said "release" controller, in its "on" position, being operative to set up operating-conditions in which said motive-means for the pump is off, said air-valve is set to exhaust air from the reservoir, said slow-flow valve is under such control as to be open at first, while the rotor-member is slowly lowering, and then to be closed subsequent to the resting of the runner on the thrust-bearing shoes, and said fast-flow valve-means is under such control as to at first prevent liquid-flow through

said valve-means in the "releasing" direction from said jacks to said reservoir under the high-pressure conditions existing while the jacks are supporting the weight of the rotor member, and then to permit liquid-flow through said valve-means in said "releasing" direction subsequent to the resting of the runner on the thrust-bearing shoes.

16. The invention as defined in claim 1, in combination with three different control-means, for respectively controlling lifting-operations, braking-operations, and jacking-operations, interlocking-means whereby only one of said three different control-means may be effectively operated at a time; said lifting-operation control-means being effective only when said rotor-member is substantially at standstill, and providing an automatic lifting-operation in which liquid is at first supplied, at a relatively rapid rate, from said reservoir, under air-pressure, through said fast-flow connection, to said hydraulic jacks until said brake-shoes are brought up substantially into engagement with said brake-ring, and in which liquid is then supplied, at a relatively slower rate, to said hydraulic jacks, exclusively through said pump-connection, with the pump operating, so as to raise said rotor-member; said braking-operation control-means being effective only when the speed of the rotor-member is less than a predetermined value intermediate between full speed and standstill, and causing liquid to be supplied from said reservoir, under air-pressure alone, through said fast-flow connection, to said hydraulic jacks; said jacking-operation control-means being effective only when said rotor-member is substantially at standstill, and causing liquid to be supplied to said hydraulic jacks through said pump-connection, with the pump operating, so as to raise said rotor-member; limit-means, associated with said lifting and jacking control-means, for limiting the amount by which the rotor-member can be lifted during each of these respective operations; and lowering-means, associated with said lifting and jacking control-means, and providing an automatic lowering-operation in which liquid is at first caused to flow, at a relatively slow rate, through said slow-flow connection, from said jacks to said reservoir, until the liquid-pressure in the jacks drops below a value intermediate between the braking air-pressure and the rotor-lifting oil-pressure, and in which liquid is then caused to flow, at a relatively rapid rate, through said fast-flow connection, from said jacks to said reservoir.

17. The invention as defined in claim 1, in combination with three different control-means, for respectively controlling lifting-operations, braking-operations, and jacking-operations, interlocking-means whereby only one of said three different control-means may be effectively operated at a time; said lifting-operation control-means being a prelubricating means for establishing oil-films between the thrust-bearing shoes and the runner, preliminarily to starting the vertical-shaft rotating machine after a period of shutdown, said lifting-operation control-means being effective only when said rotor-member is substantially at standstill, and having a "lift" position and a "release" position; said prelubricating means, in its "lift" position, being operative to set up operating-conditions in which said slow-flow valve is closed, said air-valve is set to supply air to the reservoir, said motive-means for the pump is in operation, and said fast-flow

25

valve-means is under such control as to at first permit liquid to flow through said valve-means, during relatively low-pressure oil-conditions, in the direction from said reservoir to said hydraulic jacks, until the brake-shoes are brought up substantially into engagement with the brake ring, and then to prevent liquid from flowing through said valve means in the reverse direction as the oil-pump develops an oil-pressure in excess of the air-pressure; said braking-operation control-means being effective only when the speed of the rotor-member is less than a predetermined value intermediate between full speed and standstill; said brake-operation control-means having an "on" position and an "off" position; said brake-operation control-means, in its "on" position, being operative to set up operating-conditions in which the slow-flow valve is closed, the motive-means for the pump is off, the air-valve is set to supply air to the reservoir, and the fast-flow valve-means is under such control as to permit liquid-flow through said valve-means in the direction from the reservoir to the jacks; and said brake-operation control-means, in its "off" position, being operative to set up operating-conditions in which the slow-flow valve is closed, the motive-means for the pump is off, the air-valve is set to exhaust air from the reservoir, and the fast-flow valve-means is under such control as to permit liquid-flow through said valve-means in the "releasing" direction from the jacks to the reservoir; said jack-operation control-means being effective only when said rotor-member is substantially at standstill, and having a "jack" controller and a "release" controller; said "jack" controller, in its "on" position, being operative to set up operating-conditions in which the motive-means for the pump is in operation; said "jack" controller, in its "off" position, being operative to immediately stop the motive-means for the pump; limit-means for automatically stopping the motive-means for the pump in response to a predetermined lift of the rotor-member, in the lifting- and jacking-operations, respectively; and said prelubricating means, in its "release" position, and said "release" controller, in its "on" position, being operative to set up operating-conditions in which said motive-means for the pump is off, said air-valve is set to exhaust air from the reservoir, said slow-flow valve is under such control as to be open at first, while the rotor-member is slowly lowering, and then to be closed subsequent to the resting of the runner on the thrust-bearing shoes, and said fast-flow valve-means is under such control as to at first prevent liquid-flow through said valve-means in the "releasing" direction from said jacks to said reservoir under the high-pressure conditions existing while the jacks are supporting the weight of the rotor-member, and then to permit liquid-flow through said valve-means in said "releasing" direction subsequent to the resting of the runner on the thrust-bearing shoes.

18. The invention as defined in claim 1, characterized by said slow-flow valve being normally in its closed position, and said fast-flow means

65

26

being a check-valve which at times operates to check liquid-flow in the direction from the hydraulic jacks to the reservoir, in combination with automatically responsive control-means, operatively effective when the hydraulic jacks are near their lowermost positions, and also operatively effective when the motive-means for the pump is operating, for causing said fast-flow valve-means to operate as a normal check-valve, automatically responsive control-means, operatively effective at other times, for applying to said fast-flow check-valve, an unseating force which is sufficient to open said check-valve against a liquid-pressure equipment to the air-pressure but not sufficient to open said check-valve against a liquid-pressure high enough to cause said jacks to raise said rotor-member, three different control-means, for respectively controlling lifting-operations, braking-operations, and jacking-operations, and interlocking-means whereby only one of said three different control-means may be effectively operated at a time; said lifting-operation control-means being a prelubricating means for establishing oil-films between the thrust-bearing shoes and the runner, preliminarily to starting the vertical-shaft rotating machine after a period of shutdown, said prelubricating means comprising a lift-operation control-means for causing said air-valve to be set to supply air to the reservoir, and also causing the motive-means for said pump to be operated; said brake-operation control-means, in its "on" position, being operative to cause said air-valve to be set to supply air to the reservoir, whereby liquid is supplied from said reservoir, under air-pressure alone, through said fast-flow connection, to said hydraulic jacks; said brake-operation control-means, in its "off" position, being operative to cause said air-valve to be set to exhaust air from the reservoir; said jack-operation control-means having a "jack" controller and a "release" controller, said "jack" controller, in its "on" position, being operative to set up operating-conditions in which the motive-means for the pump is in operation; said "jack" controller, in its "off" position, being operative to immediately stop the motive-means for the pump; limit-means for automatically stopping the motive-means for the pump in response to a predetermined lift of the rotor-member, in the lifting- and jacking-operations, respectively; and said prelubricating means, in its "release" position, and said "release" controller, in its "on" position, being operative to cause said slow-flow valve to open so as to lower said jacks, and pressure-responsive means, responsive to the liquid-pressure within said jacks, and operatively effective, at pressures below a value intermediate between the braking air-pressure and the rotor-lifting oil-pressure, for causing said slow-flow valve to be closed if it was open, and for preventing said slow-flow valve from being opened if it is closed.
